UNITED STATES PATENT OFFICE.

DE WITT C. BAKER, OF NEW ROCHELLE, NEW YORK.

DESIGN FOR A SET OF CHARACTER-BLOCKS.

45,249.

Specification for Design.

Patented Feb. 17, 1914.

Application filed October 18, 1913. Serial No. 796,087. Term of patent 14 years.

To all whom it may concern:

Be it known that I, DE WITT CLINTON BAKER, a citizen of the United States, residing at New Rochelle, in the county of Westchester and State of New York, have invented a new, original, and ornamental Design for a Set of Character-Blocks, of which the following is a specification, reference being had to the accompanying drawing, forming part thereof.

The figure is a view in elevation of a set of character blocks, showing my new design.

I claim:

The ornamental design for a set of character blocks, as shown.

DE WITT C. BAKER.

Witnesses:

GEO. L. BEELER,
PHILIP D. ROLLHAUS.
